Primary Examiner — Catherine R Oliver-Garcia
(74) Attorney, Agent, or Firm — Inventa Capital PLC(57) **CLAIM**

We claim the ornamental design for a wearable hand sanitizer as shown and described.

DESCRIPTION

A description of the figures or each of the figures of the drawings is as follows:

FIG. 1 is a front view of a wearable hand sanitizer;
FIG. 2 is a rear view of the wearable hand sanitizer;
FIG. 3 is a top view of the wearable hand sanitizer;
FIG. 4 is a bottom view of the wearable hand sanitizer;
FIG. 5 is a left side view of the wearable hand sanitizer;
FIG. 6 is a right side view of the wearable hand sanitizer;
FIG. 7 is a front perspective view of the wearable hand sanitizer; and
FIG. 8 is a back perspective view of the wearable hand sanitizer.
